CARBURETER.

1,126,249.

Specification of Letters Patent. Patented Jan. 26, 1915.

Application filed January 8, 1914. Serial No. 811,028.

To all whom it may concern:

Be it known that we, DAVID MITCHELL, Jr., and ISAAC VAN MITCHELL, both citizens of the United States, residing at Los Angeles, in the county of Los Angeles and State of California, have jointly invented new and useful Improvements in Carbureters, of which the following is a specification.

This invention relates to carbureters whereby vaporized petrol or other volatile fuel is vaporized and mixed with air for supply to internal combustion motors. It is well understood by those skilled in the art, that when such motors are operating at high speed there is a tendency to overdraw upon the fuel supply, due to the highly increased suction through the manifold or other means of communication between the motor and the carbureter. This causes not only a waste of fuel but produces imperfect combustion and smutting of the motor working parts and production of objectionable smoke and unburned products, even producing under certain conditions pre-ignition or ignition before complete compression, because of the over-richness of the explosive mixture. In order to do away with these objectionable working conditions, we have devised a carbureter equipped with suitable balancing valve mechanism the effect upon which of such violently increased suction is to automatically maintain a proper ratio between the component parts of the mixture namely the air and vapor, thus preventing the over-enriching. The motor is thus supplied at all speeds with the requisite amount of mixture of the proper nature.

The object of the invention is to provide a carbureter of the particular nature stated which will further be superior in point of relative simplicity and inexpensiveness of construction taken in connection with positiveness in action, durability, adjustability and compactness in form, and which will be generally superior in efficiency and serviceability.

With the above and other objects in view, the invention consists in the novel and useful provision, formation, construction, relative arrangement and combination of parts, members and features, all as hereinafter described, shown in the drawing and finally pointed out in claims.

In the drawing: Figure 1 is a top plan view, partly broken away for clearness of

illustration, of a carbureter constructed to embody the invention; and Fig. 2 is a transverse vertical sectional view of the same, taken upon the line x^2-x^2 , Fig. 1.

Corresponding parts in both figures are designated by the same reference characters.

Referring with particularity to the drawing, the improved carbureter embodying the invention is shown as combined with a fuel supply chamber A which has a fuel intake α leading to a suitable tank or source of supply. The fuel supply chamber A, in its specific construction, is not concerned in the issues of the invention. The carbureter proper has a tubular body B, composed in the form illustrated of two communicating members, b and c , the member b extending laterally from the member c , the wall 3 of the member c , opposite the member b , being provided with an inlet duct 4 communicating with a duct 5 through which fuel passes from the chamber A. One end of the chamber c is adapted to be bolted on to the manifold or intake pipe D, and carries a throttle valve E controlling the passage of explosive mixture from the carbureter to the manifold, under any suitable control.

F designates valve mechanism controlling the passage of fuel through the duct 4 into the member c , and likewise controlling the passage of air into the member b at the outer end thereof; said valve mechanism including a needle valve 6 operating with respect to a suitable seat 7 at the outlet end of the duct 4, and a puppet valve 8 applied to a suitable seat 9 at the outer open end of the member b . The needle valve 6 is mounted to play lengthwise in a bushing 10 screwed into a suitable opening in the casing B, a compression spring 11 being coiled about the needle valve between such bushing and a shoulder 12 upon the valve. A compression-adjusting nut 13 is threaded on to the outer end of the valve 6, being held against rotation by the spaced cheeks 14 upon a bracket 15 screwed to the casing member b , as at 16. The bracket 15 has two arms 15^a and 15^b to the former of which is pivoted adjacent to one end, as at 17, a lever arm 18 having a nose 18^a received between the bushing 10 and the nut 13. Another lever arm 19 is pivoted to the arm 15^b as at 20, and has a short end 20^a projecting beneath an adjusting screw 21, operatively mounted in the lever arm 18. The long end of the lever arm 18 is forked as at 18^b and received beneath

an adjusting nut 18^a at the upper end of the stem 21^a of puppet valve 8. The lever arm 19 is forked, as at 19^a and received beneath a sleeve 22, loosely surrounding the valve 5 stem 21^a and holding one end of a coil spring 23 the other end of which is held beneath the nut 18^a threaded to the upper end of such stem 21^a. The stem 21^a plays vertically through guide 24 extending transversely in 10 the casing B.

In use, as increased suction is created through the manifold D or other tubular connection and within the casing B, as permitted by the throttle valve E, the puppet 15 valve 8 is influenced to further leave its seat, the lever arms 18 and 19 being swung so that the nose 18^a tends to move the needle valve 6 farther away from its seat; the two valves thus move in step. As the valve stem 20 21^a descends the spring 23 is further compressed between the lever arms 18 and 19, such compression resisting the lowering of such valve stem, and consequently resisting the opening movement of the valves 8 and 6.

25 Thus, increase of suction or draft upon the mixture of the fuel from the chamber A and air admitted past the valve 8, is accommodated by an automatic action of the valve mechanism F tending to oppose extreme 30 unseating of the valve 6 controlling the supply of fuel and the valve 8 controlling supply of air for the mixture. The normal tension of the spring 23 may be varied by manipulating the adjusting screw 21, to relatively oscillate the lever arms 18 and 19; and the normal tension of the spring 11 35 affecting the needle valve may be regulated by turning such valve in the nut 13 which is held against rotation by the cheeks 14.

40 It is manifest that many variations may be made from the construction and combination of parts and detailed features disclosed without departing from the spirit of the invention.

Having thus described our invention, we claim and desire to secure by Letters Patent:

1. In a carbureter, a fuel inlet valve, an air inlet valve, a spring opposing the unseating of said valves, and two adjustably connected lever arms acting oppositely upon 50 said spring and one of which operatively connects said valves.

2. In a carbureter, a fuel inlet valve, an air inlet valve, a spring opposing the unseating of said valves, and two lever arms 55 acting oppositely upon said spring and one of which operatively connects said valves; there being means of operative connection between said lever arms.

3. In a carbureter, a fuel inlet valve, an air inlet valve, a spring opposing the unseating of said valves, and two lever arms acting oppositely upon said spring and one of which operatively connects said valves; there being means of operative connection 65 between said lever arms, and means for relatively adjusting said lever arms.

4. In a carbureter, a fuel inlet valve, an air inlet valve, a spring opposing the unseating of said valves, and two lever arms 70 acting oppositely upon said spring and one of which operatively connects said valves; there being means of operative connection between said lever arms, and means for relatively adjusting said lever arms; said 75 last named means comprising an adjusting screw applied to one of said lever arms and bearing against the other on the opposite sides of the fulcrum thereof.

In testimony whereof, we have signed our 80 names to this specification in the presence of two subscribing witnesses.

DAVID MITCHELL, JR.
ISAAC VAN MITCHELL.
